UNITED STATES PATENT OFFICE.

ERNEST RACZ, OF DETROIT, MICHIGAN, ASSIGNOR TO BURROUGHS ADDING MACHINE COMPANY, OF DETROIT, MICHIGAN, A CORPORATION OF MICHIGAN.

DESIGN FOR AN OFFICE CHAIR.

Application filed March 7, 1928. Serial No. 25,729. Term of patent 14 years.

To all whom it may concern:

Be it known that I, ERNEST RACZ, a citizen of the United States, residing at Detroit, in the county of Wayne, State of Michigan, have invented a new, original, and ornamental Design for an Office Chair, of which the following is a specification, reference being had to the accompanying drawing forming a part hereof, wherein—

The figure is a perspective view of a chair showing my new design.

I claim:

The ornamental design for an office chair, as shown.

ERNEST RACZ.
